BULLDOZER

Robert Sword, Linslaw, Oreg.

Application April 14, 1939, Serial No. 267,888

3 Claims. (CL 37—144)

This invention relates to bulldozers and is particularly adapted to facilitate the tilting of the blade.

The primary object of the invention is to provide a connecting framework between the bulldozer blade and the tractor that is flexible and that will permit the raising or lowering of either end of the blade without twisting the blade.

Another object of the invention is to provide connections for a bulldozer blade relative to a tractor that can be operated while the tractor is in motion for tilting, raising or lowering of the blade.

A still further object of my invention is to provide means for raising or lowering the blade equally throughout its length or raising one end of the blade without moving the opposite end or lowering one end of the blade while the opposite end is raised without in any way twisting the blade.

And a further object of my invention is to provide control levers that can be operated together in unison or operated separately for different manipulations of the blade.

These and other incidental objects will be apparent in the drawing and specification to follow.

Referring to the drawing:

Figure 1 is a side view of my new and improved bulldozer mounted on a tractor.

Figure 2 shows a rear perspective view of the bulldozer blade removed from the tractor, the framework partially broken away.

Figure 3 is a plan detail view of one of the socket fittings for holding the framework to the blade.

Figure 4 is a sectional view of Figure 3.

Figure 5 is a diagrammatical lay-out of the raising and lowering cylinders in connection with their control valves and illustrating the manner in which the control levers are hooked up thereto.

In the drawing: A commonly known type of bulldozer blade is indicated by numeral 1, but any type of blade may be employed. The tractor is indicated at 2. Rearwardly extending bars 3 and 4 are pivotally connected to the blade 1 at 5 and 6. They may be pivotally connected, as shown, through a ball and socket connection. In the drawing, I have shown a socket 7 that may be formed in two sections, as sections 8 and 9, section 9 of which may be securely fastened to the blade 1 by any suitable means, for instance welding could be employed. The half section 9 may be removed and is held in place by bolts 10. When the section 9 is in place it will support the ball 11, which is formed integral with the

bar 3, and holds each bar in a pivotally mounted relation. I do not wish to be limited to this particular type of connection, as other forms of mechanical connections might be employed, for providing a pivotally mounted connection to the bars 3 and 4 relative to the blade 1.

The opposite ends 12 of the bars 3 and 4 are so connected to the tractor 2 that such bars are capable of limited universal swinging and rocking movement relative to the spindle 13, which may be secured to any convenient location on the tractor. The connection between the spindles 13 and the bars 3 and 4 is such as to permit pivotal play of the bars with sufficient freedom of movement as to permit tilting of the blade without binding or warping of the parts. Braces 14 and 15 brace the blade 1 in two directions, that is brace the upper edge of the blade 16 from tilting backward or forward and form corner braces 20 between the bars 3 and 4 and the blade 1. Referring to Figure 2 it will be noted that the inner ends that are connected to the blade 1 of these cross braces 14 and 15 almost meet in the upper center of the blade relative to its length.

25 The braces 14 and 15 are connected to the side frames 3 and 4 by suitable pivot socket fittings 17 and they are connected to the blade by means of the socket connections 18. These connections permit pivotal movement of either end 30 of the braces 14 and 15. It is apparent that the front end of the push arms and of the diagonal brace on each side must be pivotally connected to the blade to permit swinging movement of the arm and brace on one side as a unit about an axis running through the points of the pivotal connections of these parts. The braces may be formed in two parts, such as tubes 19 and 20 telescopically related and locked at any desired point, as by locking means 21, to provide for 35 angular adjustment of the blade.

40 The blade may be raised and lowered by any suitable raising or lowering means. I have illustrated bell cranks 22 pivotally mounted at 23 to a main frame structure 24. Fluid pressure cylinders 25, having their pistons 26 connected to the arm 27 at 28 control the position of the bell cranks 22. A connecting link 29 connects socket fitting 30 on each of the braces 14 and 15 adjacent its one end remote from the blade to the 45 corresponding bell crank 22 by pivot connection 31.

50 In the operation of my new and improved bulldozer blade the cylinders 25 are controlled by suitable valves 32, governed by handles 33 either simultaneously, separately or in opposite direc-

tions. For instance if the handles 32 were held together and manipulated in either direction the valves 32 would act in unison supplying fluid to the cylinders 25, raising or lowering the bulldozer blade without tilting either end. In case it is desired to raise one end of the blade while the other remains stationary one of the handles 32 would be operated, controlling one of the valves 32 and supplying only one of the cylinders with operating fluid. In this case one end of the blade would be raised or lowered. If the levers 33 were operated in opposite directions one end of the blade would be raised and the opposite end would be lowered.

I will now explain the main feature of my invention. By observing Figure 2 closely it will be noted that if one end of the blade were raised, for instance the left side relative to the drawing, there would be a hinging action on line A—B which would allow the blade to be raised or lowered without twisting. At the same time the brace 14 would brace the blade on its vertical line, while acting as a brace against side thrust between the side frame 3 and the bulldozer blade 1. A corresponding hinged line B—C must be considered in the operation of my new and improved bulldozer, these lines A—B and B—C indicate the principle of my invention. By placing the braces as shown, solid support is given the bulldozer blade as heretofore described, while also providing flexibility when either end of the blade is raised or lowered, commonly known as tilting the blade.

I do not wish to be limited to the particular mechanical embodiment, as other types of mechanical combinations may be used, still coming within the scope of the claims to follow.

What is claimed to be new is:

1. A bulldozer, bars extending from the lower outer ends of the bulldozer to a road vehicle, the connection of the bars to the road vehicle being mounted for limited universal swinging and rocking movement, said bars supporting the bulldozer for movement with respect to the vehicle, braces intermediate the bars and bulldozer, the braces being connected at one end to the bars at a distance from the bulldozer, and being connected at the bulldozer at the upper end of the latter and adjacent the vertical central line of the bulldozer the ends of a brace and bar being connected to the bulldozer on one side of the center line thereof and arranged to permit swinging of the arm and brace as a unit about an axis running through the connection of said arm and brace to the bulldozer, a power means operative from the vehicle, connections from the power means, said power means serving to actuate either or both of the braces at will, the operation of one such brace tending to tilt the bulldozer on the pivotal support of the opposite bar, and the operation of both of said braces serving to raise or lower the bulldozer through the medium of the pivotal connected bars.
2. A construction as defined in claim 1 wherein the connection between the power means and the braces is adjacent the connection of the braces to the bars.
3. A construction as defined in claim 1 wherein the braces are of telescopic formation, capable of being secured at different lengths.

ROBERT SWORD.
